US00D879729S

(12) **United States Design Patent** (10) **Patent No.:** **US D879,729 S**
Wang et al. (45) **Date of Patent:** **** Mar. 31, 2020**

(54) **ELECTRICAL MODULE**

(71) Applicants: **Microduino Inc.**, Westlake Village, CA (US); **Meike Technology (Beijing) Ltd.**, Beijing (CN)

(72) Inventors: **Zhenshan Wang**, Westlake Village, CA (US); **Jian Hu**, Westlake Village, CA (US); **Kejia Pan**, Westlake Village, CA (US); **Xi Li**, Westlake Village, CA (US); **Bin Feng**, Westlake Village, CA (US)

(73) Assignees: **Microduino Inc.**, Westlake Village, CA (US); **Meike Technology (Beijing) Ltd.**, Beijing (CN)

(**) Term: **15 Years**

(21) Appl. No.: **29/609,504**

(22) Filed: **Jun. 30, 2017**

(51) LOC (12) Cl. **13-03**

CLAIM

The ornamental design for an electrical module, as shown and described.

DESCRIPTION

FIG. 1 is a front perspective view of an electrical module, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a back perspective view thereof.

1 Claim, 4 Drawing Sheets
